UNITED STATES PATENT OFFICE.

MILLER M. DEEM, OF READING, PENNSYLVANIA, ASSIGNOR OF ONE-HALF
TO P. & F. MANUFACTURING CO., OF SAME PLACE.

DESIGN FOR A POMMEL-CUSHION FOR VELOCIPEDe-SADDLES.

SPECIFICATION forming part of Design No. 29,078, dated July 19, 1898.

Application filed December 10, 1897. Serial No. 661,459. Term of patent 7 years.

To all whom it may concern:

Be it known that I, MILLER M. DEEM, a citizen of the United States, residing at Reading, in the county of Berks and State of Pennsylvania, have invented a certain new and original Design for Pommel-Cushions for Velocipede-Saddles, of which the following is a specification.

In the accompanying drawings, which illustrate my design, Figure 1 is a plan view of a cushion made in accordance with my design, and Fig. 2 is a cross-section on the line 2 2 of Fig. 1.

The leading feature of my design consists in an oblong shell-like structure A, arched in cross-section, as shown in Fig. 2, having a rounded forward end B and terminating in two divergent arms C.

The walls D of the cushion curve gradually outward, and the ends E of the divergent arms slant rearwardly to the base-line of the walls D, their inner edges F uniting at a point G on a line passing longitudinally through the center of the part A.

Having described my invention, I claim—

The design for a pommel-cushion for velocipede-saddles substantially as set forth.

In testimony whereof I affix my signature in presence of two witnesses.

MILLER M. DEEM.
